UNITED STATES PATENT OFFICE.

JAMES M. MUNYON, OF PHILADELPHIA, PENNSYLVANIA.

DESIGN FOR A MEDICAMENT VESSEL FOR INHALERS AND NASAL DOUCHES.

SPECIFICATION forming part of Design No. 30,532, dated April 11, 1899.

Application filed February 25, 1899. Serial No. 706,885. Term of patent 14 years.

To all whom it may concern:

Be it known that I, JAMES M. MUNYON, a citizen of the United States, residing in the city and county of Philadelphia, State of Pennsylvania, have invented and produced a new and useful Design for a Medicament Vessel for an Inhaler and Nasal Douche, of which the following is a specification, reference being had to the accompanying drawings, forming part thereof.

The leading features of my design for a medicament vessel for an inhaler and nasal douche are, first, a vessel having a channel in its side below the mouthpiece thereof, and, next, a cap from which said vessel depends and to which said mouthpiece is attached.

Figure 1 represents a side elevation of a medicament vessel for an inhaler and nasal

douche embodying my design. Fig. 2 represents a vertical section thereof.

In the drawings, A designates a vessel which is pendent from the cap B.

C designates a mouthpiece, and D designates a nasal tube, both on the cap B.

On the side of the vessel A is the channel E, which is below the mouthpiece C.

Having thus described my invention, what I claim as new, and desire to secure by Letters Patent, is—

The design for a medicament vessel for an inhaler and nasal douche substantially as shown and described.

JAMES M. MUNYON.
